SHEET-FED INTAGLIO ROTARY PRINTING
MACHINE

Paul Koch, Plauen, Germany

Application January 7, 1935, Serial No. 780
In Germany January 8, 1934

1 Claim. (Cl. 101—157)

This invention relates to a sheet-fed intaglio rotary printing press.

One of the objects of the invention is to avoid the waste of usable printing plate surface involved at printing presses of this type whereas heretofore the printing cylinder, either if made half the size of the impression cylinder, had to make two revolutions for each sheet printed whereof one was idle, or it was only half covered with engraving to be reproduced, one half of its copper surface, if copper coated cylinders were used, being wasted or, if plate cylinders were used, not being covered by the printing plate.

Another object of the invention is to nearly double the output of sheet-fed intaglio rotary printing presses without unduly increasing the printing and delivering speed which is limited by the requirements for sufficient drying of the sheets, and without necessitating the use of double feeding and delivering stacks as heretofore thought indispensable.

With these and other objects and advantages in view my invention consists in the equipment of the machine not only with a feeding device of known type comprising two kinds of mechanically or air suction operated grippers the one of which being adapted to begin registration of the sheet at a moment when it is still over or under-lapped by the preceding sheet, the other being adapted to engage the preceding registered sheet and to convey it toward the impression cylinder, but by dimensioning the impression cylinder to which the sheets are fed so that the circumference thereof is less than one-fourth larger than the sheet length, the form cylinder being of the same size as the impression cylinder.

This construction affords the added advantage that the printed sheet passes the press operator with the printed side up to facilitate supervision. For this purpose the sheet is supplied to the printing mechanism on the side where the doctor is located on the form cylinder.

By way of example, one form of the invention is illustrated in the accompanying drawing.

The sheets are supplied from the pile 1, by means of several types of mechanically or air suction operated grippers 7 and 8, to the impression cylinder 2 which passes them through the printing mechanism and then to a chain

conveyor which on the path 3 delivers them to the pile 4 or to a drying device.

The impression cylinder 2 is dimensioned so that its circumference is less than one-fourth of the length of the sheet larger than the latter. The space thus remaining on the impression cylinder between the first part of the rubber blanket and the end thereof need only be large enough to accommodate the grippers required for catching the sheets. The sheet feeding device comprises, in known manner, two sets of grippers 7 and 8, the gripper 7 picking up the sheets from the pile and registering them for the second set of grippers 8 which supplies them to the impression cylinder 2 in such a way that in the meantime the first set of grippers 7 can in the meantime lift the next sheet from the pile.

The form cylinder 5 is as large as the impression cylinder 2, and the doctor 6 presses against the form cylinder 5 on the same side on which the sheet feeding device is positioned. This makes it possible to pass the sheets around the impression cylinder 2 and then over the path 3, so that they may be examined by the machine operator.

The reference character 9 indicates gripper rods which either are connected with the conveyor chain 10 or, on the path 15 from pulley 11 to pulley 12. Conveyor chain 10 is guided by pulleys 13 and 14. This conveying mechanism permits a certain amount of drying of the printed sheets before they are stacked on the pile 4.

I claim:—

A sheet-fed intaglio rotary press comprising an intaglio form cylinder, an impression cylinder having a set of grippers thereon, said cylinders cooperating with each other and the diameters of the cylinders being approximately equal, a sheet feeding device disposed adjacent to the impression cylinder and feeding thereto one sheet at each revolution of the cylinders, and the entire circumference of the form cylinder being capable of printing except for the space required for said set of grippers on the impression cylinder, and a delivery device for stripping the sheets off the impression cylinder and being disposed in a position and direction over that in which the sheets are fed.

PAUL KOCH.
